Graves Griffet

UNITED STATES PATENT OFFICE.

GRAVES GRIFFITH, OF SAN FRANCISCO, CALIFORNIA.

INTERNAL-COMBUSTION HYDRAULIC PUMP.

1,327,036.

Specification of Letters Patent.

Patented Jan. 6, 1920.

Application filed September 20, 1918. Serial No. 254,930.

To all whom it may concern:

Be it known that I, GRAVES GRIFFITH, a citizen of the United States, residing at San Francisco, in the county of San Francisco,

5 State of California, have invented certain new and useful Improvements in Internal-Combustion Hydraulic Pumps, of which the following is a specification.

My invention relates to internal combustion hydraulic pumps having twin combustion heads operating alternately, and connected freely to a common body having non-return inlet and outlet valves, and from which a liquid is expelled and into which it 10 enters following the combustion of a combustible charge in one or the other of the said combustion heads.

A principal object of my invention is to provide, in a pumping apparatus of the character named, means whereby the dynamic energy of the explosion of a combustible charge may be transmitted, as a kinetic force, to a body of liquid and the momentum thus obtained applied to the compression of 15 an elastic fluid, the force thus secured being again transformed into power through the agency of a turbine.

An additional object of my invention is to provide, in a pumping apparatus of the character described, means whereby the impulse imparted to a body of liquid by the explosion of a combustible charge upon its surface may be utilized in the compression of 20 an elastic fluid, the energy thus secured being applied to the discharge of the liquid under a regulated pressure, an application particularly fitting it for pumping liquids into reservoirs at elevation, or for hydraulicking where physical conditions were such as to 25 prevent the establishment of a head sufficient to provide the necessary pressure.

A further object of my invention is to provide, in a pumping apparatus of the kind named, means whereby the degree of compression of a combustible charge may be varied from those requiring extraneous means for ignition, to compressions sufficiently high to produce the heat necessary for ignition. Supplementary to the preceding is the 30 provision of means for regulating and governing, both as to time and quantity, the return liquid flow whereby the compression of the combustible charge is effected.

In the accompanying drawing, forming a 35 part of this specification and in which similar parts are designated by similar reference

characters, Figure 1 represents a vertical longitudinal, sectional principally, view of my invention as applied to an impulse wheel.

Fig. 2 is a detail, viewed from in front, of the mechanism operating the cam-shaft that actuates the head valvular system.

Fig. 3 is an enlarged detail, through 2—2, of the mechanism operating the fuel-chamber valve.

Fig. 4 is a detail, partly in section, of the spring-control of the current-operated gate actuating the movable parts.

Fig. 5 is a view similar to that of Fig. 1, but showing the arrangement of the valves and their actuating mechanism at an opposite phase of the cycle from that shown in Fig. 1. In Fig. 1, the arrangement of these valves and their actuating mechanism is that at the conclusion of a working stroke in head 1, while the arrangement of these parts, as shown in Fig. 5, is that preceding the entry upon a working stroke in the head 1'.

Fig. 6 is a detail of the fuel pipe 45 and check valve 60.

Fig. 7 is a detail of the means, dependent upon pressure, for making and breaking the electric circuit, when the spark is relied upon for the ignition of the fuel charge.

Fig. 8 is a detail of the cams 52, 52'.

Fig. 9 is a modification, in detail, of the rack and pinion operating valve 42.

Referring more particularly to the drawing, 2 indicates an inlet conduit leading from a source of liquid supply, opening into a body-portion 4, and having therein a plurality of non-return valves 3. Combustion heads 1, 1' communicate freely with the body-portion 4 and are supplied with exhaust valves 58, 58' having seats 59, 59' and open to atmosphere through openings 61, 61'. The stems of the valves 58, 58' play through guides 56, 56' and have heads 53, 53' against which the cams 52, 52' bear in opening these valves. Springs 54, 54' close the valves 58, 58' immediately the cams 52, 52' pass beyond the heads 53, 53', and must be of a strength sufficient to resist atmospheric pressure at time of lowest negative pressure within the twin heads following an explosion and the cooling of the gases. Passages 44, 44' lead respectively from the combustion heads 1, 1' to a common fuel-chamber 43, and are closed alternately by a valve 42 carried in bearings 41. The swinging motion necessary to this action is secured

through the operation of a rack 37 and pinion 38, driven from a crank 33 borne by a shaft 32, transmitted through a crank-rod 36 jointed at 35 and working in guides 39, with crank-bearing at 34. The crank-shaft, 32, bearing the cams 52, 52' and the crank 33, is supported at either end in bearings carried by the arms 29, 29' and has a bevel-wheel 31 in mesh with a second bevel-wheel 28 carried on the shaft 27 of the ratchet-wheel 26. The ratio of the diameter of the bevel-wheel 31 to the diameter of the bevel-wheel 28 is that of 1 to 2. A means is provided for actuating this valvular mechanism comprising a quadrant-toothed ratchet-wheel 26 operated by a crank-rod 23 terminating in a ratchet 24 carrying guide-lips 25 and a spiral spring 62 for maintaining position on and contact with the ratchet-wheel 26. The crank-rod 23 is connected-up with a rocker-arm 30 borne by a shaft 40 bearing a current-gate 55 and a coiled spring 50 in a casing 35. The lower portion of the crank-rod 23 is enlarged 22 and slotted 21, serving as a source of moving power and guide for the pin and arm 20 in operating the rotatory valve 19. Leading from the body-portion 4 is an outlet conduit 4' controlled by a diaphragm 10 carrying a plurality of non-return valves 7. Connecting freely with the conduit 4' is a chamber 6 containing an elastic fluid, the compression of which serves to store energy. An outlet 8, from the conduit 4', comprising a nozzle 12 controlled by a valve 11 having a hand-wheel 9, is provided, through which current for the operation of an impulse-wheel 13, 16 passes. The shaft 14 of the impulse-wheel 13, 16 is carried in bearings having a base-support 15.

Compression of the fuel charge is obtained through transference of pressure from the chamber 6 to the body-portion 4 following the induction of the fuel charge and liquid into their respective compartments. The means provided for this purpose comprise a return conduit 17, connecting the chamber 6 with the body-portion 4, having therein valves 18 and 19, the former being hand-operated and limiting the return liquid flow, the latter being operated from the crank-rod 23 and governing this flow as to time. The fuel-charge enters the fuel-chamber 43 through the pipe 45 having a check valve 60.

The apparatus functions as a two cycle internal combustion displacement pump, with the difference that instead of relying upon a resurge of a liquid column for both exhaust and compression, the action is simplified to the extent that the exhaust takes place near the close of the working stroke with the gases still under some degree of tension, followed immediately by the reseating of the exhaust valve and a negative pressure, due to the cooling of the slight re-

maining residue of gases, and the induction of both a new fuel charge and liquid supply, and the admission of a predetermined degree of pressure for the compression of the fuel charge and its ignition.

In further illustration of the operation of the device, let it be assumed that ignition has taken place in combustion head 1, and that the seating of valve 58 has been retarded slightly for purpose of explanation, as shown. The gas expansion incident to the explosion has driven liquid from the body-portion 4 through the valves 7 into the outlet conduit 4' and onward into the chamber 6, compressing the elastic fluid therein. The forward rush of this current carries with it the current-gate 55 through a quadrant swing, throwing the arm 30 from the dotted position to a vertical one, thrusting upward the rod 23, the which movement throwing the pin and arm 20 from the right to the position shown, closing the valve 19, while at the same time the ratchet termination 24 has thrust over the ratchet-wheel 26 through a quarter revolution, giving thereby a half turn to the cam-shaft 32. The mass movement of the liquid, through its momentum, continuing after the force generating it has expended itself, increases the space of negative pressure already referred to as having been created by the cooling and contraction of the trifling residue of gases, thereby greatly adding to the induction pull for the new gas and new liquid charge.

The moving having come to a state of rest, the coiled spring 50 swings the current-gate 55 back to the vertical, or dotted line, position, at the same time reversing the direction of movement of the rod 23, thereby opening the valve 19 and admitting pressure for the compression of the newly inducted fuel charge, and operation of the ignition means. The ignition means, where the heat generated by high pressures are not relied upon for the purpose, comprise a head 49, actuated by a spring-governed piston 51, contacting with a spring-contact 48, insulated and having wire 47 connection, through a battery, with a spark-plug 46.

Upon ignition of the fuel charge in combustion head 1', a repetition of the movements previously described takes place, with the exception that, upon the semi-revolution of the cam-shaft 32, it is the cam 52' that engages the head 53' opening temporarily the valve 58' for exhaust, and the crank 33 operating to give the opposite throw to the valve 42 opening the passage 44 and closing passage 44'. Reaction results as before, with the cycles continuing at will. For the initial start, it will be required that there be introduced, manually or mechanically, a fuel charge into one or the other of the combustion heads 1, 1', and compression, as well, into the chamber 6.

Starting or stopping operation, under right conditions, is accomplished by opening or closing the valve 18, the timing of the cycles being also secured through the same source, 5 the degree of opening controlling it.

Whatever the direction of application of energy thus derived and stored, it may be directed through some such valve-controlled agency as that represented by 8, 11, 12.

10 I claim:

1. In an internal combustion hydraulic apparatus, a body-portion having inlet and outlet conduits, non-return inlet and outlet valves therefor, twin combustion heads 15 communicating freely with the said body-portion, a fuel-chamber common to the said twin combustion heads, passages from said fuel-chamber communicating respectively with the said combustion heads, a valve 20 within the said fuel chamber for closing alternately the said passages, an ignition means communicating with the interior of the said fuel-chamber, and means, dependent on pressure, for rendering the said ignition 25 means operative.

2. In an internal combustion hydraulic apparatus, a body-portion having inlet and outlet conduits, non-return inlet and outlet valves therefor, twin combustion heads communicating freely with the said body-portion, a fuel-chamber common to the said twin combustion heads, passages from the said fuel-chamber communicating respectively with the said combustion heads, a 30 valve within the said fuel-chamber for closing alternately the said passages, an ignition means communicating with the interior of the said fuel-chamber, means, dependent on pressure, for rendering the said ignition 35 means operative, means for exhausting, alternately, the products of combustion from the said twin combustion heads, and a common means for actuating both the said exhaust means and the said fuel-chamber 40 valve.

3. In an internal combustion hydraulic apparatus, a body-portion having inlet and outlet conduits, non-return inlet and outlet valves therefor, twin combustion heads communicating freely with the said body-portion, a fuel-chamber common to the said twin combustion heads, passages from the said fuel-chamber communicating respectively with the said twin combustion heads, a valve 45 within the said fuel-chamber for closing alternately the said passages, an ignition means communicating with the interior of the said fuel-chamber, means, dependent on pressure, for rendering the said ignition 50 means operative, means for exhausting, alternately, the products of combustion from the said twin combustion heads, a common means for actuating both the said exhaust means and the said fuel-chamber valve, a 55

shaft and ratchet for actuating the said 60 common means, and a means, discharge and spring governed, for actuating the said shaft and ratchet.

4. In an internal combustion hydraulic apparatus, a body-portion having inlet and outlet conduits, non-return inlet and outlet valves therefor, twin combustion heads communicating freely with the said body-portion, a fuel-chamber common to the said twin combustion heads, passages from the said fuel-chamber communicating respectively with the said combustion heads, a valve 65 within the said fuel-chamber for closing alternately the said passages, an ignition means communicating with the interior of the said fuel-chamber, means, dependent on pressure, for rendering the said ignition 70 means operative, means for exhausting, alternately, the products of combustion from the said twin combustion heads, a common means 75 for actuating both the said exhaust means and the said fuel-chamber valve, a shaft and ratchet for actuating the said common means, a means, discharge and spring governed, for actuating the said shaft and ratchet, a compression chamber, and a controlled return-pressure means connecting the said compression chamber and the said body-portion, comprising a conduit having valves 80 therein and means actuated by the said shaft 85 for the operation of one of the said valves.

5. In an internal combustion hydraulic apparatus, a body-portion having inlet and outlet conduits, non-return inlet and outlet valves therefor, twin combustion heads communicating freely with the said body-portion, a fuel-chamber common to the said twin combustion heads, passages from the said fuel-chamber communicating respectively with the said combustion heads, a valve 90 within the said fuel-chamber for closing alternately the said passages, means for introducing a combustible mixture into the said fuel-chamber, an ignition means 95 communicating with the interior of the said fuel-chamber, means, dependent on pressure, for rendering the said ignition means operative, means for exhausting, alternately, the products of combustion from the said twin combustion heads, a common means for actuating both the said exhaust means and the said fuel-chamber valve, a shaft and ratchet for actuating the said common means, a means, discharge and spring governed, for actuating the said shaft and ratchet, a compression chamber, and a controlled return-pressure means connecting the said compression chamber and the said body-portion, comprising a conduit having valves therein 100 and means actuated by the said shaft for the 105 operation of one of the said valves.

GRAVES GRIFFITH,
